Primary Examiner — Cathron Brooks*Assistant Examiner* — Teddy Falloway(74) *Attorney, Agent, or Firm* — Griggs Bergen LLP(57) **CLAIM**

The ornamental design for a panel display, as shown and described.

DESCRIPTION

FIG. 1 is a front perspective view of a panel display in a closed configuration;

FIG. 2 is a front perspective view of the panel display thereof in an open configuration;

FIG. 3 is a top plan view of the panel display of FIG. 1;

FIG. 4 is a top plan view of the panel display of FIG. 1;

FIG. 5 is a right side elevational view of the panel display of FIG. 1;

FIG. 6 is a left side elevational view of the panel display thereof;

FIG. 7 is a rear elevational view of the panel display thereof; and,

FIG. 8 is a bottom plan view of the panel display thereof.

The broken lines shown are included for the purpose of illustrating portions of the panel display that form no part of the claimed design.
